PAPER ROLL HOLDER

Joseph A. Poirier, Woonsocket, R. I.

Application October 11, 1944, Serial No. 558,159

5 Claims. (Cl. 242—55.2)

This invention relates to a paper roll holder and more particularly to a holder intended as a mounting for a roll of toilet tissue, one object of the invention being to provide a holder adapted to be mounted against a wall and serve as a carrier for a roll of paper which is to be unwound therefrom and a cardboard core for the roll then removed from the holder and a new roll applied.

Another object of the invention is to provide a holder including an arm having an attaching bracket at one end and an abutment at its other end for preventing accidental displacement of the roll from the holder.

Another object of the invention is to provide a holder wherein the arm carries depending webs near its inner and outer ends which serve to prevent upward movement of the roll on the arm and also serve as means for frictionally preventing too rapid rotation of the roll when paper is withdrawn therefrom.

Another object of the invention is to so shape the depending web near the outer arm that a roll must be tilted in order to slide it onto the arm past an upstanding finger at the outer end of the arm, the roll being then returned to a horizontal position in which the outer end of the roll is engaged by the finger and the roll prevented from sliding longitudinally off the arm.

Another object of the invention is to provide a holder which is simple in construction and may be cheaply manufactured as a single casting.

The invention is illustrated in the accompanying drawing, wherein:

Fig. 1 is a view showing the holder in side elevation and a roll of toilet tissue applied thereto.

Fig. 2 is a sectional view on the line 2—2 of Fig. 1.

Fig. 3 is a sectional view on the line 3—3 of Fig. 1.

Fig. 4 is a sectional view taken longitudinally through the holder and illustrating the manner in which a roll of paper is applied thereto.

Fig. 5 is a perspective view of the holder.

This improved paper roll holder is formed as a single casting and has an arm 1 which extends from an attaching bracket 2 through which openings 3 are formed to receive screws 4 by means of which it is to be firmly secured against a wall or equivalent support 5. The arm is circular in cross section and, while it has been shown solid, it will be understood that it may be hollow in order to reduce weight and save material required to make it. The arm is of sufficient length to pass through the roll of paper 6 and protrude from the outer end of the core 7 which is formed from

5 a tube of cardboard, as shown in Fig. 1. Referring to this figure, it will be seen that near its outer end the arm 1 carries an upstanding finger 8 which overlaps the outer end of the roll and prevents the roll of paper from slipping longitudinally off the arm after the roll has been applied to the holder. A short web 9 extends downwardly from the inner end of the arm and is integrally united with the lower portion of the bracket 2 as well as with the arm. Therefore, this web will serve as a reinforcement for the arm as well as serving to engage in the core 7 of the roll and frictionally grip same to prevent too rapid rotation of the roll while unwinding paper therefrom. 10 A longer web 10 extends downwardly from the arm near the front end thereof and attention is called to the fact that this long web or tongue is of triangular shape and tapers toward its outer end so that it has a sloping lower edge 11. By 15 so forming the web 10, a roll of toilet tissue may be tilted and thrust onto the arm 1, as shown in Fig. 4, pressure against the outer end of the roll being continued until the roll moves past finger 8 and assumes the horizontal position indicated 20 by dotted lines in this figure and shown in full lines in Fig. 1. The upstanding finger 8 will prevent the roll from sliding longitudinally off the outer end of the arm and, since the web or tongue 10 is disposed within the front end of the core 25 1 and engages the inner surface thereof, it will prevent the roll from having tilting movement on the arm which would allow the roll to shift forwardly over the finger 8 and slip off the front end of the arm. Since the web 10 has frictional engagement with the core, it will cooperate with the 30 web 8 to resist rotation of the roll and prevent it from turning too freely when pull is exerted upon the paper to unwind paper from the roll. Resistance to free rotation of the roll upon the arm 35 40 also allows paper unwound from the roll to be easily torn loose. After all the paper has been withdrawn, pressure may be applied to the core from opposite sides thereof and the core will thus be collapsed by transverse pressure and its transverse shape changed from circular to elliptical, the longest diameter being vertical. When the core is in this vertically elongated shape, it may be shifted longitudinally over the finger and readily removed from the arm so that another roll may 45 be applied to the holder. It will thus be seen that a roll of toilet tissue may be readily applied to the holder and rotatably carried thereby, accidental displacement of the roll being prevented during use and too rapid rotation of the roll being also prevented.

Having thus described the invention, what is claimed is:

1. A paper-roll holder comprising a bracket adapted to be secured against a support, an arm projecting forwardly from said bracket, a finger projecting upwardly from the front end portion of said arm for overlapping the front end of a paper-roll and retaining the roll upon the arm, a tongue projecting downwardly from the forward portion of said arm, said tongue extending longitudinally of said arm and being tapered toward its front end to provide a lower edge extending forwardly at an upward incline, the rear end of said tongue being vertically arcuate and merging into the rear end of the inclined lower edge, and a web projecting downwardly from the rear end portion of said arm formed integral with the arm and the front face of said bracket.

2. A paper-roll holder comprising a bracket adapted to be secured against a support, an arm projecting forwardly from said bracket, a finger projecting upwardly from the front end portion of said arm for overlapping the front end of a paper-roll and retaining the roll upon the arm, a member under the front end portion of said arm for engaging in a core of a paper-roll extending longitudinally of the arm and having a lower edge extending forwardly at an upward incline, and a web for engaging in a core of a paper-roll projecting downwardly from the rear end of said arm.

3. A paper-roll holder comprising an arm having mounting means at its rear end and an up-

standing finger at its front end, a tongue projecting downwardly from the forward portion of said arm, said tongue having its lower edge extending forwardly at an upward incline whereby a paper-roll having a tubular core may be tilted and forced along the arm toward the rear end thereof to a position for resting upon the arm with said finger overlapping the front end of the roll, and a web depending from the rear end of said arm for engaging in the rear end of the core to retard rotation of the roll on the arm.

4. A paper-roll holder comprising an arm having mounting means at its rear end and an up-standing finger at its front end, a tongue projecting downwardly from the forward portion of said arm for entering the core of a paper-roll thrust upon the arm and engaging the forward portion of the core to hold the roll against upward movement on the arm out of abutting engagement with said finger, and a web at the rear end of said arm for entering the core of the roll and frictionally engaging the core and retarding rotation of the roll.

5. A paper-roll holder comprising an arm having mounting means at its rear end and an up-standing finger at its front end, a wedge carried by the forward portion of said arm for engaging in the core of a roll and resisting upward displacement of the roll on the arm, and a brake-member carried by the arm for engaging in the core of the roll and retarding rotation of the roll.

JOSEPH A. POIRIER.
